TELEPHONE SYSTEM

Bernard Anthony Hensler, London, England, assignor to Siemens Brothers & Company Limited, London, England

Application August 17, 1935, Serial No. 36,703
In Great Britain August 22, 1934

14 Claims. (Cl. 179—18)

The present invention relates to telephone systems in which connections are set up over selecting switches which are set in accordance with markings applied to them.

5 In this invention a selecting switch has associated with it for the purpose of setting it a device operable by coded signals transmitted over a signalling circuit from apparatus for setting up a connection automatically and the device 10 according to a setting assumed in response to a coded signal makes marking connections to bring about the setting of the selecting switch to a particular position or group of positions. The device may conveniently take the form of relays 15 less in number than the marking connections they are adapted to make, the marking connections being made over serially connected contacts of the relays, and may be included in a control circuit available in common to a number of selecting switches.

In a multi-office area the selecting switches are commonly set under the control of a register sender in which the digits characteristic of the wanted number are stored and are retransmitted as impulse trains to the selecting switches in turn as they become connected up. In the present invention the registers, after being set transfer their settings in code form over signalling wires to the code responsive devices associated with the selecting switches as these become connected up. When the registers of a register sender receive their settings from an operator's position they may be, and usually are, set by the transmission of the digits in code form from a key sender.

35 When a selecting switch extends the connection to a succeeding circuit the associated device is disconnected and a signal is transmitted to the register sender to bring about the application of the code signal for the marking of the succeeding selector. This method of setting selecting switches is convenient and rapid for switches in the same exchange as the register sender especially when the selecting switches are high speed motor driven switches having a hunting speed of

40

45 200 contacts or more a second, but since other exchanges may be involved in a connection the register sender is also adapted to transmit digits in impulse form. To bring about the change from code sending to impulse sending a signal is transmitted to the sender from apparatus associated with a line outgoing from the exchange, this signal differing from that transmitted after a switch has switched through a connection. The signal for bringing about the application of a

50

55 succeeding code marking may be a fleeting sig-

nal of the nature described in British Patent No. 422,200 while the signal for bringing about the change in the method of digit transmission may be of less fleeting nature which takes effect on apparatus unresponsive to the fleeting signal or it may be a signal transmitted by the application of a potential different from that normally applied during code reception or employed for the aforementioned purpose. 5

For the connection of the registers a single switch may be employed which in its early positions connects up the registers in turn to receive the digits and later connects the registers to the signalling wires for the transfer of their settings in code form to the selecting switch code responsive device and for applying the requisite markings to the bank of a sending switch for impulse transmission. 10 15

The code responsive device for the marking of a selecting switch is conveniently situated in a common control circuit and may be connected to the signalling wires over back contacts of the selector switching relay, the change-over of these contacts on the operation of the switching relay serving to transmit the fleeting signal before referred to.

A selecting switch may be arranged to be set in accordance with two digits. In such a case a single motion switch may be included in the common control circuit and be marked by the operation of the code responsive device for the first digit the switch hunting for the marked position and preparing a marking circuit for the selecting switch. The code responsive device is then released and the signal to the register sender transmitted by relay operation in the control circuit and the operation of the code responsive device by the second digit may effect a direct marking connection to the selecting switch bank, the testing circuit for the selecting switch including a wiper of the signal motion switch in the position to which it was set by the first digit and the contacts of the code responsive device as determined by the second digit. The second digit may determine that a hunting operation by the selecting switch is required or that the switch is to select an individually marked line. 30 35 40 45

In the case of trunk line connections the trunk selecting switches may be set in accordance with the invention, the connection being completed over a connecting circuit, which may be a cordless one at an operator's position. To simplify the arrangements for connecting trunk lines and to lessen the work of the operators it may be arranged to connect repeaters into circuit if the 55

trunk lines connected require it. Further, the repeaters may, for simplicity be furnished with a small number of, for example, two, fixed values of gain and the characteristics of the trunk lines with which connection is made may determine which of the values of gain is to be inserted. The repeaters may be in a group accessible to any connecting circuit on the trunk switchboard or common to an operator's position or group of 10 positions and may be connected to a connecting circuit by means of a hunting switch. Relays in the connecting circuit operable from incoming and outgoing trunk line circuits may determine by their operation that a repeater is required and 15 the value of gain to be inserted.

An embodiment of the invention as applied to a trunk exchange is shown by way of example in the accompanying drawings. In the drawings Fig. 1 shows a both way trunk line circuit with 20 a distributor for connecting incoming calls to a connecting circuit at an operator's position or to a lamp display circuit; Fig. 2 shows a cordless connecting circuit with which a repeater may be associated automatically if required by the characteristics of the trunk lines which become connected to the connecting circuit, two values of gain being provided for one of which is inserted automatically in accordance with the characteristics of the trunk lines connected; Fig. 3 shows 25 a first trunk selector, Fig. 4 a second trunk selector, Fig. 5 a reverting selector all set by markings applied by relays in response to a code and Fig. 6 a register sender.

All trunk calls are set up by operators by means 30 of cordless connecting circuits and the selecting switches in the trunk exchange are high speed motor driven switches set in response to a marking. This marking is applied by a set of 4 code relays the relays being operated from the sender 35 by a code, that is to say one or a combination of code relays is operated depending on the application of potential at the sender to one or a combination of 4 wires which extend between the sender and the selecting switches. The same 40 wires serve for the transmission to the sender of a transient signal when the connection is switched through at a selecting switch to bring about the application of the code marking for the setting of the next selector. Provision is 45 made in the sender for the transmission of from one to four digits in code form and the remainder, up to eight digits in all, in the usual impulse form.

The trunk selectors have the minimum of apparatus individual to them, the control being 50 vested in common circuits. Provision is made for the storage of calls that cannot be extended by the second trunk selector due to congestion and for alternative routing in the case of some trunk groups. The second trunk selector is also enabled 55 to search in a trunk group or to select an individual line in a group and to remain in contact with that line if it is found busy. The first trunk selector has access both to second trunk selectors and to trunk lines, no storage facilities being provided in the latter case. The reverting trunk selector becomes connected to the answering side of 60 a connecting circuit by means of a finder switch and gives access to second trunk selectors.

An operator normally has a connecting circuit 65 assigned for use and which is seized by the distributor associated with a trunk line on the initiation of an incoming call, and the connection is set up by the operator by means of a key strip and the necessary keys and relays in a circuit common to all the connecting circuits at

her position. This circuit is not shown in detail, only those keys and apparatus necessary for the understanding of the invention being shown below the broken line in Fig. 2. The position circuit follows the general lines of that shown and described in British Patent No. 401,394. 5

The operator setting up a connection has complete supervision of it while it is in being.

If a connecting circuit is not assigned an incoming call causes the distributor to test in to 10 a free lamp in a lamp display on which all incoming calls for which connecting circuits are not assigned are queued up in order of their arrival. The calls are dealt with in order of arrival when a connecting circuit becomes assigned, 15 the release of the call at the head of the queue and the stepping up of the others being performed automatically as described in the copending application of Bernard A. Hensler and Charles L. Peters, Serial No. 37,484, filed Aug. 23, 1935. 20

The several figures forming the drawings to the present specification and the circuits shown therein will now be considered in detail.

Consideration will first be given to Fig. 1. The circuit shown is connected to a trunk line incoming on the left hand side of the drawing and has access over a distributor switch to connecting circuits, such as that shown in Fig. 2, the leads to which are shown outgoing on the right hand side of the drawing. If a connecting circuit is not assigned at the time the switch is hunting the switch makes connection with a call lamp display which may be of the kind shown in the copending Hensler and Peters application. Besides having access to connecting circuits at incoming positions the switch can gain access to a delay position to deal with calls which the operator receiving them has been unable to complete at the time and which have been ticketed and become reverting calls. A calling lamp and answering key such as would be provided on a delay position are shown in a broken line rectangle in this figure, the lamp and key being individual to the incoming trunk line. Access to the circuit for reverting calls is had over second trunk selectors such as that shown in Fig. 4 the leads from which enter the figure at the upper edge. 30 35 40 45

The distributor switch is of the motor driven type in which the circuit of a small electric motor is controlled by a latch magnet designated LM, the magnet when operated disengaging a latch from the switch driving mechanism and connecting up the motor circuit. On de-energisation the latch magnet disconnects the motor circuit and re-engages the latch with the driving mechanism. 50 For purposes of description in this and other figures where motor driven switches are employed the energisation and de-energisation of the latch magnet will be assumed to include the starting and stopping of the motor. The latch magnet LM is under the control of a high speed relay T. The switch is of the 200 outlet type in which the contacts are connected in the equivalent of two sets of arcs of 104 contacts each, one set being accessible over back contacts of a wiper switching relay WS, and the other set over front contacts of this relay. An arc of contacts comprises in fact two arcs of 52 contacts each wiped over in succession by the two ends of a staggered wiper equivalent to one wiper moving over an arc of 104 contacts. 55 60 65

A call is initiated on receipt of ringing current over the trunk line, a suitable call responsive device being connected to the wire RRW. The response of this device to a call effects the con- 70 75

nection of earth to wire STW the effect of which is to bring about the operation of relay ST over a circuit including contacts *gs4*, *ss7*, key NSK, and contact *ss6*. Relay ST operates and locks 5 up over contact *st1*. Contact *st2* closes a circuit for the operation of a recording device to record the receipt of an incoming call over the trunk, contact *st4* disconnects earth from a group control relay GP associated with a storage device for 10 outward trunk calls which cannot be completed immediately while demand working is in force. Relay GP is earthed over contacts in each trunk circuit of a group of trunks. Contact *st5* opens the test wire PO incoming from second trunk 15 selectors and contact *st1* closes a circuit for the magnet LM of the distributor switch. Magnet LM operates in a circuit from earth over contacts *t1*, *s1*, *ds3*, *tf5*, *st1*, magnet winding, relay RA to battery and the switch is set in motion. As soon 20 as the wipers leave their normal position the off-normal contacts *on* close. For the sake of description it will be assumed that a connecting circuit connected to the arcs associated with the wipers connected to the front contacts of relay 25 WS has been assigned by an operator at an incoming position. The switch rotates until the last bank contacts are encountered whereupon a circuit is closed from earth over wiper 5, contacts *ws4*, *ss4*, *dt2*, rectifier R, both windings of relay T, 30 contacts *an5*, *ws5*, wiper 1, relay WS and its shunt to battery. Relay T operates in this circuit to stop the motor by opening contact *t1* which removes a short circuit from relay S which may operate in series with the magnet LM and locks 35 up over its front contact *s1*, this contact being of the make-before-break type. Magnet LM will not operate in series with relay S owing to the resistance of the latter. Shortly after the operation of relay T relay WS operates, disconnecting 40 the odd numbered wipers and connecting up the even numbered wipers. In doing so it opens its own operating circuit and that of relay T but relay WS has locked up meanwhile over contact *an4*, its early clasing contact *ws1* and contact *on*. 45 Relay T however releases and short circuits relay S and causes the motor to restart in search of the assigned connecting circuit. The last contact in the dotted arc of wiper 4 is commoned with the last twelve contacts in the inner arc and earth 50 over contacts *ss3*, *s3*, wiper 4 short circuits relays SS and DT and prevents their operation. Consequent on the switch advancing through its normal position contact *on* opens but owing to the high speed at which this contact is passed relay 55 WS does not release. The switch continues in rotation and when the contacts connected to the assigned connecting circuit are reached relay T again operates the circuit being from earth over wire N, the application of which will be clear 60 from the subsequent description of the circuits of Fig. 2, wiper 6, contacts *ws4*, *ss4*, *dt2*, relay T, wiper 8a, wire P, to battery over shunted relay B in the connecting circuit. Relay S re-operates and relays DT and SS operate over contacts *on* 65 and *s5* and hold over contact *ss1* and relay ST is released by the prolonged opening of contact *ss6*. The speaking wires are switched through over contacts *ss2*, *s2*, and *ss3*, *s3* and the higher resistance upper winding of relay T after being 70 short circuited by contact *t1* is disconnected at contact *ss5* the relay remaining held over its lower resistance lower winding. During the releasing period of relay ST battery is connected over resistance *R1* which is of a value to denote 75 the nature of the trunk line, contacts *st6*, *s4*, *ss4*,

ws4, wiper 6, wire N to relay NA in the connecting circuit.

On the release of relay ST wire N is connected to earth over back contact *st6*, contact *gs1*, relay SY and contact *z2*. Relay SY is not operated at this time owing to the resistance in the circuit. Contact *ss7* opens the operating circuit for relay ST and connects relay Z to wire STW to enable it to respond to a re-ring should one be given. Contact *dt3* opens in the circuit 10 over wire PO and contact *dt4* in the group control circuit. Contact *dt5* substantiates contact *st2*.

If the night service key NSK had been thrown, relay TF would have operated instead of ST and locked up over contacts *tf1* and *st1*. Contact *tf2* closing, the lamp CL on a special transfer position is lit, and on seeing the lamp glowing the operator at that position presses the key ANK associated with the lamp CL and individual to the 15 trunk to operate relay AN. Relay AN locks up over contacts *an1* and *tf4*, opens the circuit of lamp CL at contact *an2* and at contact *an3* closes a circuit for relay ST which thereupon operates, releases relay TF, holds relay AN at contact *st3* 20 and starts the switch. Contact *an4* operates relay WS and contact *an5* substitutes wiper 8b for 7 and 8a thereby causing the switch to test over the wire PS for the connecting circuit assigned at the transfer position, the earth for the operation 25 of relay T being applied over wire N. After the release of relay ST relay AN is held over contact *s6*.

If for any reason an operator at an incoming connecting position is unable to deal with a call 30 she may, by applying battery potential to the negative wire, operate relay TF over its left hand winding to transfer the call to a transfer position. Relay TF locks up as previously described and lamp CL is lit. On the operation of relay AN 35 consequent on the depression of key ANK by the transfer operator relay T is released followed by relay S. The switch now advances to its normal position magnet LM being energised over contacts *on*, *s5*, and *st1*, and when the normal position is 40 reached the switch stops and relay SS is released. Relay ST can now operate over contacts *ss6*, *tf3* 45 and *an3* and the switch continues in search of the assigned transfer operator's connecting circuit. 50

If, when a call arrives no connecting circuit is assigned the distributor switch on being set in motion is advanced until a free lamp display circuit is found. This is marked by battery potential on the wires LD or if the lamp display be 55 full, a battery potential will be found on wire LDO connected to the arc of wiper 8a. Assuming for the moment that a free lamp in the display is available then relays T and WS are operated when the switch reaches the last contacts in the arcs of the odd numbered wipers and relays and the switch is then restarted in the manner before described and continues in motion until the free display lamp is found. The circuit for relay T is then from earth over contacts *ss5*, *ds2*, arc and wiper 6, contacts *ws4*, *ss4*, *dt2*, rectifier R, relay T, contacts *an5*, *ws5*, wire LD to battery. Relay S reoperates but relay SS does not as it is short circuited over arc and wiper 4, contacts *s3* and *ss3*. 60 A circuit is now closed from earth over contacts *ss2*, *s2*, *ws2*, wiper 2, commoned contacts preceding the last contact, upper winding of relay DS to battery. Relay DS operates and locks up over 65 its lower winding and contacts *ds1* and *ws2* and 70 75

opens the operating circuit for relay T at contact *ds2*. Relay T however holds over its lower winding to earth over contact *t1*. Contact *ds4* operates relay DT which locks up over contacts *dt1* and *st1* and contact *ds3* prepares a circuit for magnet LM. Contact *t1* by connecting earth over the low resistance lower winding of relay T marks the particular lamp circuit busy to other testing distributors.

10 When an operator is free to take the calls, that is, after preceding calls, if any, indicated in the lamp display have been answered and the call in question is now at the head of the queue the circuit over wire LD is opened and relays T and S are released. The switch now advances until the assigned connecting circuit is reached, magnet LM being operated over contacts *on*, *s5*, *ds3*, *t5* and *st7* until the normal is reached whereupon the relay WS releases, releases relay DS and the 20 switch is again started, magnet LM being now energised over contact *t1*.

When no free lamp display is available the switch rotates until the overflow outlet LDO is reached whereupon it is stopped, the overflow outlet 25 lets from the several switches being connected over individual resistances to a common battery terminal. Release from the overflow outlet takes place when a connecting circuit is assigned.

In the event of a re-ring being received over 30 the trunk line after relay SS has been operated relay Z is operated and locked up over contacts *z1*, *sy1* and *s6*. Contact *z2* disconnects steady earth potential from wire N and connects this wire to an intermittent earth potential circuit 35 thereby causing the operator's supervisory lamp to flash. On seeing this the operator throws her speaking key, thereby reducing the resistance in the circuit to an amount which enables relay SY to operate. Relay SY operating contact *sy1* releases relay Z which in turn restores the steady 40 earth potential on wire N.

After the conversation over the trunk line is completed the distributor is restored to normal by the opening of the circuit over wire P. Relays 45 T, S and AN if operated, release and the switch rotates to normal whereupon relays SS and DT release.

When the trunk line is wanted for an outgoing call test is made for battery over the test 50 wire PO incoming from the second trunk selector contacts *ra3*, *dt3*, *st5* and shunted relay GS. Relay GS operates and at contact *gs1* connects earth over relay SY to the wire SO. Contact *gs4* disconnects wire STW from relay ST and connects it to relay Z, contact *gs5* operates the traffic 55 recorder for outgoing calls, contact *gs2* closing causes lamp ORL to glow steadily and contact *gs3* opens in the group control circuit.

To ring over the trunk line relay RR is operated by battery connected to the positive wire 60 over a key in the connecting circuit. Contact *rr1* closes to start up the ringing motor-generator if it is not already running and contacts *rr2* and *rr3* apply ringing current over wire CSW to the 65 trunk line.

Whenever the switch motor is connected up 70 relay RA operates in series with the latch magnet LM and the motor windings and at contact *ra1* closes a circuit for a delayed alarm relay. Contact *ra2* connects lamp ORL to a wire which is earthed intermittently to cause the lamp to flash and contact *ra3* opens in the test wire PO to guard against interference by an attempted outgoing call.

75 The incoming connecting circuit shown in Fig.

2 is accessible over the both way trunk circuit of Fig. 1 and is also provided with means whereby by means of a reverting selector such as that shown in Fig. 5 access may be had over the answering side of the connecting circuit to the 5 trunk circuit for the purpose of calling back over the trunk line for a call which has suffered delay and has been released.

A repeater with fixed values of gain is adapted to be connected automatically to the connecting 10 circuit over a hunting switch, its insertion and that of one of two values of gain being dependent on the trunk lines with which connection is made by each side of the connecting circuit.

The connecting circuit is a cordless one and 15 provides a straight through speaking connection with or without the insertion of a repeater after the call has been set up, supervisory relays being connected to the supervisory wires N and S, on either side of the circuit. The wires leading towards the bottom of the figure are connected to a position circuit common to all the connecting circuits at a position and which contains keys and relays for monitoring and supervisory and other purposes, a sending key strip and keys and relays 20 for the starting of a register sender. The position circuit may follow the general lines of that shown in the British Patent previously referred to, only those parts necessary for the proper understanding of the present invention being shown or 25 referred to. The connecting circuit itself follows the general lines of that described in the aforementioned specification suitably modified to enable the automatic switching in of a repeater to 30 be accomplished.

When an operator is free to deal with an incoming call she throws her speaking key SP thereby operating relay SK. Contacts *sk1* and *sk2* split the speaking wire circuit and connect the calling side to the operator's circuit, and contacts *sk3* and *sk4* connect the answering side to the operator's circuit. Contact *sk5* closes a circuit for relay SL over contact *b5* and a contact of the speaking key and relay MN in the position circuit, contacts *sk6* and *sk7* close points in circuits for relay B and contact *sk8* short circuits the upper winding and connects earth over the low resistance lower winding of relay SK to prevent the operation of a relay similar to SK in another connecting circuit and thus bringing about interference by the connection together of two connecting circuits. Relay SL operates and disconnects the high resistance winding of relay SK at contacts *s16* and holds relay SK over its low resistance winding independently of the speaking key. Contacts *s12* and *s13* close further points in circuits for relay B, contact *s14* extends the outgoing wire P to the position circuit and contact *s15* prepares a circuit for relay SD. The 40 connect answer key CA is now thrown.

If there are calls waiting and connected to the lamp display circuit a contact of this key, not shown, in its operated position brings about the release of the call from the display by earthing the wire LD shown to the right of Fig. 1 thereby 45 releasing relay T in that figure. The method of applying the earth to release the call at the head of the queue is shown in the co-pending Hensler and Peters application. The call distributor in the trunk circuit now commences to hunt for the assigned connecting circuit which is marked by battery potential over shunted relay B, contact *sk6*, release answer key RA, connect answer key CA, contacts *s13*, *rs2*, and wire P.

If there had been no calls connected to the 75

lamp display circuit earth would have been connected to wire EN over a contact corresponding to contact *en1* in Fig. 2 of the above mentioned copending application and an incoming call finding a connecting circuit already assigned the test relay of the call distributor would be connected at one end to this earth over wire EN, contact *b2* and wire N and the other end to battery over wire P and the circuit previously traced.

10 In the case of the connecting circuit of a special control position battery would be found over relay B contact *sk6*, key RA, contacts *sk7*, and *sk2* and wire PS.

When a call distributor tests in to the assigned 15 circuit relay B is operated and provides a holding circuit for itself at contact *b7* to wire P or over contact *b4* to wire PS independently of key CA. Contact *b2* disconnects wire N from wire EN and connects it to relays NA and NC one or both 20 of which as the case may be being operated from battery over resistance *R1* in the trunk circuit and indicative of the characteristics of the line wire N. This circuit is completed during the operating lag of relay BA which is heavily slugged 25 at its armature end and the relay or relays operated lock up over their left hand windings and contact *b3* which also applies earth for the operation of relay BA. If the trunk line is one which, apart from the line to which it is to be connected 30 does not require the insertion of a repeater relay NA only is operated. Contact *b5* changes the circuit for relay SL by including a relay CG which operates and opens the circuit over which the release of a call from the queue is brought about as 35 described in the co-pending application, and contact *b6* lights the circuit engaged lamp CE. Relay BA operating contact *ba1* disconnects wire N from relays NA and NC and connects it to the answering supervisory relay AS and contact *ba2* 40 lights the answering supervisory lamp ASL. Relay AS operates but the resistance is too high to allow relay SY in the trunk circuit to operate until, the speaking key being thrown, contact *as1* shunts relay AS to increase current flow over 45 wire N. Contact *as2* extinguishes lamp ASL.

The operator now receives particulars of the wanted connection and proceeds to set it up in the following manner. She presses the send call key SCK which by closure of contacts not shown 50 starts a sender coupling switch (SCS Fig. 6) hunting for the position which when found is connected to a register sender. As soon as the sender is connected a lamp is lit to inform the operator of the fact, and she then keys up the 55 number of the wanted connection or so much of it as is to be completed automatically on the key strip common to the position, the digits keyed being transmitted by means of a code to register relays in the sender. She then presses a start 60 key in the key strip which operates a relay to disconnect the start lead for the sender coupling switch, sends forward a starting impulse to the sender and closes contact *st* thereby operating relay SD. Relay SD locks up over contact *sd6*, its 65 low resistance winding and contact *st*, and at contact *sd1* operates relay SE. Contacts *sd2*—*sd5* disconnect the speaking wires from the operator's circuit and connect them over contacts *se4*—*se7* to the sender, contacts *se2*, *se3* and *se8*, 70 *se9* connecting wires NP and NN through to the sender likewise, thus completing four wire connections between the sender and selecting switches over which the code for marking the selectors is transmitted. Contact *se1* disconnects 75 the high resistance upper winding of relay SD.

A further result of the operation of the key SCK is the connection of earth over contact *sd1* and wire ST to operate relay K in the first trunk selector (Fig. 3). Operation of relay K extends this earth back over wire P over which the relay is ultimately held. The key also closes an alternative circuit over a contact of the speaking key for lamp CE.

The code markings are now transmitted by the sender which by the operation of a relay in the 10 position circuit has become disconnected from the key strip and connected to the wires positive, negative, NP and NN on the outgoing side of the connecting circuit. It will be realised that if a call is to be set up by means of a reverting selector the send answer key SAK will be operated 15 in place of the send call key SCK and the sender will become connected to the answering side of the connecting circuit.

When the connection has been set up and the 20 speaking key is restored relays SK, SL, SD and SE release. Contact *sk2* falls back before contacts *sk6* and *sk7* open thus providing that the circuit over relay B is continuous during the release of relays SK and SL. Relays NB and ND 25 are now connected to wire NP to which battery over a resistance will be connected in the trunk line circuit. Relay NB operates. If the resistance is of low value ND will also operate. The operation of relay NC or ND denotes that a repeater is 30 required in the connection and accordingly a circuit is closed from earth over contacts *rc1*, *nc1* and/or *nd1*, *nbl*, *nal*, *h1*, relay ST of the first free repeater connected to a chain start circuit to battery. Relay ST operates and connects 35 latch magnet MU of the coupling switch of the seized repeater over contacts *st2*, *h1* and *t1*. Contact *st1* brings about the closure of the heating circuit for the filaments of the amplifiers, contact *st3* connects relay T to wiper 8 of the coupling switch the arc contact of which appropriate to the connecting circuit requiring the repeater is marked by battery potential over shunted relay RC and contacts *nc2* and/or *nd2*, *nb2* and *na2*. When the marked connecting circuit is 40 found relay T operates in the above traced circuit and brings about the release of the latch magnet MU and the removal of a short circuit about relay H at contact *t1*. The same contact also connects earth over the low resistance lower 45 winding of relay T to mark the connecting circuit busy to other coupling switches. Relay H operates in series with magnet MU but the magnet is not operated in this circuit and the relay locks up over contact *h1* and at contact *h2* opens 50 the homing circuit for the coupling switch. Contact *h3* substantiates contact *st3*, contact *h4* connects the gain control relays to wiper 1, contact *h5* prepares a circuit for relay HA, contact *h6* substantiates contact *st1* and contact *h7* disconnects the start wire from relay ST and connects it to the start wire of the next repeater connected in chain like manner to a ring start 55 wire. Relay GA operates over wiper 7 the resistance, contact *st1*, contacts of ring call key RCN and ring answer key RAN to earth. If both relays NC and ND are operated the resistance in this circuit is short circuited and relay GB operates in addition to relay GA. Contact *ga1* 60 completes the circuit for relay HA which operates and at contacts *ha3*—*ha1* connects the repeater to the connecting circuit over wipers 1-6 of the coupling switch. Contacts *ha8* opens a further point in the homing circuit of the switch and 65

70

75

75

- contacts *ha1* and *ha2* open to connect balancing networks to the repeater connection. Contacts of relay GB and other contacts of relay GA are associated with the potentiometers for the control of the gain to be inserted, one or other of two fixed values of gain being inserted. When relay T operated relay RC was operated. Contact *rc1* opens the start circuit, contact *rc2* re-operates relay SD over its upper winding and contact *st5* to split the speaking wire circuit, contact *rc3* prevents the earth over contact *sd6* and the lower winding of relay SD shunting out any other SD relay which it may be required to operate for the purpose of setting up another connection, contact *rc6* prevents operation of relay SE and contacts *rc4* and *rc5* extend connections from the repeater over wipers 3 and 4 to key MON which when thrown extends these connections to a monitoring circuit.
- 20 Supervisory relay CS is operated over wire S from earth in the outgoing trunk circuit when the connection has been extended thereto and while the speaking key is thrown contact *cs1* shunts the relay to allow relay SY in the trunk line circuit to operate. Contact *cs2* extinguishes the supervisory lamp CSL which was lit over wire SY and contact *cs3* starts the time checking device MR.
- 25 The operator may ring over either trunk line by pressing the appropriate key RAN, RCN. This disconnects relay GA which in turn releases relay HA to disconnect the repeater during ringing and connects battery over the positive wire to operate relay RR in the trunk line circuit, the result of which has already been described.
- 30 The operator may release either side of the connection by the depression of the appropriate key RA, RC, and she may, as at the end of conversation, release the connection by depressing the release key RL, thereby opening the circuit over wiper P simultaneously and releasing relay T in the trunk line circuit and relay H in the first trunk selector or reverting selector circuits, thus initiating the release of the connection.
- 35 Relays NA and NB release also the operated relay NC, ND thereby releasing relay T. Contact *t1* falling back short circuits relay H which releases and releases in turn relays GA and HA. The homing circuit of the coupling switch is now closed over contacts *on1*, *ha8*, *h2*, *st2* and magnet MU and the coupling switch is homed in known manner.
- 40 If the operator wishes to recall a subscriber over an incoming trunk line, for instance after she has cleared a connection which has been subjected to delay she throws her speaking key SP and the send answer key SAK thereby operating relay RS over its winding (I) and contact *st1*. Contact *rs1* connects earth over contact *b1* to the start wire IN to operate relay ST or GT in the reverting selector circuit, Fig. 5, to cause a finder switch associated therewith to rotate in search of the connecting circuit which is marked in its banks by battery over the shunted relay B, contacts *sk6*, key RA, contacts *sk1*, *rs3*, *rs2*, and wire P. When the finder switch reaches the marked contact position relay B operates, opens the starting circuit at contact *b1* thereby closing a locking circuit over the front of this contact and contact *rs1* for winding (II) of relay RS.
- 45 The further results of the operation of relay B are as previously described. The key SAK being thrown in place of the key SCK the circuit for the application of the code markings to the selectors is prepared over contacts *se2*—*se5* and the

answering side of the connecting circuit and the finder switch of the reversing selector.

The operation of relay TC is as described in British patent No. 401,394.

It will be remembered that when the operator threw key SCK earth was extended over wire ST to operate a coupling relay K in the first trunk selector. Such a selector is shown in Fig. 3 and it will be seen to be an 8 wiper 100 outlet motor driven switch controlled by a common control circuit which includes relays for receiving the digits in code form for the setting of the switch. The control circuit is provided at the rate of one per operator's position and is multiplied directly to the individual trunk selectors. The trunk selector is set by one digit and outlets may be paired, that is to say a group of outlets may be utilised to serve any two digits, a signal being sent forward to the succeeding circuit to effect discrimination between the digits which can cause an outlet to be taken into use.

Since the control circuit is individual to an operator's position and the operator at an incoming connecting circuit position can only deal with one call at a time it is not necessary to make any test for a selector with a free control circuit the fact that an operator is free to deal with a call and has a free connecting circuit being sufficient to determine that the first trunk selector and its associated control are both free. When relay K operates in the above traced circuit it locks up over contacts *k1*, *h1*, wire P and key RC in the position circuit. Contact *k2* lights the circuit engaged lamp CE in the connecting circuit over wire E and contact *k3* the calling supervisory lamp CSL over wire SY. Contact *k4* applies earth to the code relays AW, AX, AY, AZ in preparation for the reception of the coded digit from the sender, contact *k5* prepares the circuit of the latch magnet LM of the switch and contacts *k6*, *k7* and *k8* other preparatory circuits. The receipt of the coded digit from the sender effects operation of one or a pair of the code relays over the corresponding wires, positive, negative, NP, NN by the application of battery thereto. A circuit is thereupon closed from earth over contacts *t1*, *ta4*, one or a pair of the contacts *aw6*, *ax6*, *ay6*, *az6*, contacts *k5*, *ha3*, latch magnet LM, relay RA to battery and the switch is started in search of a free outlet to a further trunk selector or to an impulse repeater in local junction lines. The required group is marked in the contact arc of wiper 8 by earth over rectifier R, both windings of relay T and two or more of the contacts of the code relays according to their condition. The circuit then continues over wiper 8, contact *k8*, wiper 6, wire P to battery on a free link, e. g. over relay GS in Fig. 1. When such is encountered high speed relay T operates and removes the short circuit from winding (I) of relay TA and the direct earth from magnet LM so that relay TA is switched into the magnet circuit. The relay operates but its resistance is too great to allow the magnet to continue operated and in consequence the latter releases and the switch is brought to rest. Contact *ta1* closes early thereby connecting winding (II) of relay TA in a locking circuit over contact *k4*. Contacts *ta3* and *ta4* opening later disconnect the code relays and latch magnet respectively and contacts *ta5* and *ta6* connect earth over contact *k6* to operate relays H and HA. Relay H operating opens the locking circuit of relay K, its operating circuit having been opened at contact *on2* when the switch moved off-normal, and extends earth over

wire P to hold relays H and HA, contact *h2* extending this earth to effect short circuiting of relay T. The remaining contacts of relay H and contact *ha4* switch the connection through to the switch wipers 1 to 5. The opening of the circuit of the code relays at contact *ta3* transmits a signal to the sender to prepare for the application of the code marking for the succeeding selector. Contacts *ha1* and *ha2* substantiate contacts *k2* and *k3* and contact *ha3* holds open the circuit of magnet LM. Relays K and T release to be followed by relay TA whereupon the control circuit is free for further use.

If digits are paired a cross connection of winding (I) of relay PP is made to terminals shown adjacent to this winding and connected to contacts of the code relays in such manner that relay PP is operated from earth over the contacts of the code relays in response to one of the digits of a pair, this digit being the one for which a discriminating signal is to be transmitted forward. When relay PP is operated and on the operation of relay TA earth is applied over contact *ta5*, winding (II) of relay PP, contact *k7*, wiper 1 to the succeeding selector circuit wherein it brings about a discriminating action. Relay PP is held by its winding (II) until the discriminating action has been taken, relay K and consequently relay TA being held over contacts *ta2* and *pp2*.

The release of the selector takes place consequent on disconnection of earth from wire P. Relays H and HA release and the switch is homed consequent on the energisation of magnet LM over contacts *ha3*, *k5* and *on1*, the last mentioned contact opening when the wipers reach their normal position to release magnet LM and stop the switch.

If, during its search the selector is unable to find a free outlet in the marked group it rotates to a last contact position to which battery is connected in the arc of wiper 6 for the purpose of operating relay T. Relay T, which is connected directly to the last contact in the arc of wiper 8 and relays TA, H and HA operate as previously described and busy tone is transmitted from apparatus connected to the last contacts in the arcs of wipers 1 and 2. At the same time battery is connected over wiper 4 to wire NN to bring about the release of the sender.

The relevant terminals corresponding to dead or spare lines marked by the group marking contacts of the code relays are connected to the last contact in the first section of the arc of wiper 8, that is, to contact 50. If a code relevant to a spare line is received the switch is stopped in this position, the corresponding contacts in the arcs of wipers 1 and 2 being connected to a N. U. T. circuit, wire NN being connected to battery over wiper 4 as before.

Relay RA operates whenever the latch magnet or switch motor is energised and at contacts *ra1* and *ra2* close circuits for a delayed alarm relay and for the flashing of lamp RL respectively.

If the selector has routed the call to an impulse repeater in a local junction line, battery will be connected over one of the wipers 1, 2 or 3 to effect circuit changes in the sender for the setting of further switches by impulses instead of by markings.

Continuing with the description and assuming that the connection is to be set up over a second trunk selector the circuits of such a selector shown in Fig. 4 will now be described.

The second trunk selector is also an 8 wiper

100 outlet motor driven switch with a common control circuit. The switch is adapted to be set in accordance with two trains of impulses and, depending on the value of the second train to search in a marked group or to be set to an individual trunk line. The switch may also search for a free alternative route if no direct route is free in groups of trunks provided with this facility and in the case of a setting to an individual line it may remain on the contacts of that line if busy until the line becomes free. Calls which cannot otherwise be completed are directed to a storage device and when a line in the required group becomes free the stored call is released and the selector is started to research the group for the free line. Like the first trunk selector the switch is marked in accordance with a code received from the sender, the code relays being situated in the control circuit and designated AW—AZ. In the control circuit is a contact ratchet driven reverse drive digit switch the magnet of which is designated DM and the wipers *DM1* to *DM8*. The digit switch is adapted to receive a signal from the first trunk selector to differentiate between pairs of digits received at the first trunk selector in respect of which the same group of outlets is searched.

The test for a free selector involves the test for its associated control circuit and to meet this condition the test wire extends into the control circuit where battery potential indicates a free condition. This circuit extends over wire P, contacts *h1*, *on2* of the selector switch, *jb2*, contact 1 in the bank of wiper DMS of the digit switch in the control circuit, shunted relay B to battery. When the circuit is taken into use relay B is operated over this circuit in series with relay T in the first trunk selector. Contact *b1* closes a circuit for relay JB which operates and opens its contacts *jb2*, and *jb3*—*jb6* in the test-in circuits associated with the selector shown and other selectors served by the same control circuit. Contact *b2* closes a circuit over contact 1 and wiper *DM1*, magnet contact *dm* and magnet DM which operates and interrupts its own circuit stepping the switch to its second contacts. Relay K operates in series with relay B over contact *jb2* and at contact *k1* closes a circuit for itself against the opening of contact *on2* and at contacts *k2* to *k8* makes connections between the control circuit and the selector taken into use. Meanwhile contact *jb1* having closed, and assuming for the moment that no earth has been applied to wire PP in the preceding circuit relay PF operates over its right hand winding in series with magnet DM. Magnet DM will not operate in this circuit. Contact *pf1* closing completes a locking circuit for the relay dependent on relay PTA and independent of magnet DM. Contact *pf2* applies earth over contacts *gs2*, *ca1*, and *pta3* to the code relays preparatory to the transmission by the sender of the coded digit and contacts *pf3* and *pf4* prepare circuits for relay PTA.

If at the time the circuit was taken into use earth was present on wire PP denoting one of a pair of digits by which the selector may have been selected magnet DM is operated over wiper *DM2* contact *jb1* and wire PP until the twelfth contact position is reached. The effect of this is to cause different groups of outlets to be marked in response to the received digit depending on the value of the preceding digit. In this case marking is effected in positions 13-22 of the digit switch instead of in positions 2-11 as would be the case if no discriminating signal had

been received. Relay B holds over contact *j6* after the digit switch leaves its second position.

The code digit marking is now received from the sender and one or a pair of the code relays is operated applying earth to the corresponding contact in the arc of wiper DM8; at the same time the closure of contacts 1 of the code relays concerned completes a circuit over contacts *p3* or *p4*, *pt1*, *pta2* for magnet DM. The magnet operates and by self interruption of its circuit at contacts *dm* drives the digit switch until the contact marked over wiper DM8 is reached whereupon relay PT is operated to stop further drive by opening contact *pt1*. This contact connects relay PTA in the circuit to earth over which the magnet was operated and the relay operates and locks up over contacts *pta1* and *j6*. Contact *pta1* releases relay PF but during the slow release of this relay the code relays operated were released by the change over of contact *pta3*. Contact *pta2* disconnects the magnet circuit and contact *pta4* releases relay PT.

If the group of trunks designated by the received digit is to be searched the digit "1" is now transmitted by the sender and this is arranged to bring about the operation of relay AW alone. Contact *aw1* closes a circuit for relay GS from earth over contacts *aw1*, *ay1*, *az1*, *aw1*, *p3*, relay GS to battery. Relay GS operates and locks up over contacts *gs1* and *b1*. Contact *gs2* releases relay AW causing the register sender to prepare for the connection of the next coded digit, contact *gs3* closes a circuit for the selector latch magnet LM, contact *gs4* closes in the test circuit of the selector, contact *gs5* prepares a circuit for stopping the selector in connection with a storage circuit and contact *gs6* opens a testing circuit associated with spare numbers.

The digit switch is not stepped by the second digit "1" but the latch magnet LM of the selector operates in a circuit from earth over contacts *ta1*, *tb1*, *hc2*, *ca3*, *gs3*, *k2*, *ha4*, magnet winding relay RA to battery. The selector is rotated in search of a free trunk, designated by battery potential on the outgoing test wire PO and when such a trunk is found relay TA which is of the high speed type operates in a circuit over contacts *in6*, *at3*, wiper DM5, marking wire, contact arc and wiper 1, contacts *k1*, *gs4*, *k6*, wiper 6, wire PO to battery. Contact *ta1* disconnects direct earth from the latch magnet circuit thereby bringing about the release of the magnet and the stopping of the switch and removes a short circuit from the right hand winding of relay HC. Relay HC now operates in series with the winding of magnet LM but the magnet itself does not operate. Relay HC locks up over contacts *hc1* and *b1* and opens the latch magnet circuit at contact *hc2*. Contact *hc3* closes a circuit over contact *k3* for relays H and HA which operate and switch the connection through. Contacts *ha4* and *h6* open further points in the circuit of magnet LM against the release of relay K. Relays H and HA hold to earth connected to wire P. The change over of contact *h1* releases relays K and B and these relays releasing bring about the release of all the relays in the control circuit. On the falling back of contact *b2* a homing circuit is closed for the digit switch which thereupon drives to its first position. The selector is released at the end of the conversation by the disconnection of earth from wire P resulting in the release of relays H and HA. The latch magnet LM is now operated from earth over contacts *on1*, *h6*, *k2* and *ha4* and the se-

lector switch is driven rapidly to its normal position. It being assumed that the second trunk selector has selected an outgoing trunk line earth over retard coil R in the trunk line circuit (Fig. 1) brings about the release of the sender. 5

If instead of "1" being received as the second digit one of the numbers 2—0 is received the selector does not search in the group designated by the first digit but selects the line designated by the second digit. As one of the relays AX, AY, AZ is operated by the second digit relay IN is operated in place of relay GS and locks up over contacts *in1* and *b1*. Contacts *in2* and *in4* open in the busy signal circuits against the operation of relay CA, contact *in3* completes the 15 circuit for magnet LM, contact *in5* disconnects relay HC and prepares a circuit for relay CA and contacts *in6* and *in1* close the test circuit. The selector is now rotated in search of the line which is marked over relay TA, contacts *in1*, relevant contacts of the code relays, marking wires, contact arc and wiper 8, contacts *in6*, *at3*, wiper DM5 in the position to which it was set by the first digit, arc and wiper 1, contacts *k1*, *gs4*, *ca6* to battery. When this line is reached 20 relay TA operates in the above traced circuit stops the switch and allows relay CA to operate. Relay CA locks up over contacts *ca1* and *b1* and at contact *ca6* disconnects the test circuit and releases relay TA and connects this relay over 25 contact *k6* and wiper 6 to the test wire to test the condition of the selected line. Contacts *ca2* and *ca5* close in the busy signal circuit, contact *ca4* releases relay IN and contact *ca7* releases the code relay or relays. Contact *ca3* changes 30 over to guard magnet LM and prepare an operating circuit for relay HC. Relay IN releasing a circuit is closed for relay HC over its right hand winding, contacts *in5*, *tb1*, *hc2* and *ca3*. Relay HC operates and locks up over its left hand winding with the result previously described 35 if the line is free. If the line tests busy relay TA does not re-operate after the changeover of contact *ca6* consequently the right hand winding of relay HC is short-circuited and this relay 40 does not operate. Busy tone and flash is now transmitted back over the positive wire and wire S respectively to give a tone to the operator and flash her supervisory lamp. The selector and control circuit are held until the line becomes 45 free or they are released by the operator. In the former case, the re-connection of battery to the outgoing test wire when the line becomes free brings about the operation of relay TA which is followed by HC, H, and HA as before and the connection is switched through and the control circuit is released. The busy signal is disconnected and the operators' answering supervisory lamp glows steadily, the earth for this lamp being connected in the trunk line circuit 50 (Fig. 1) over contact *z2*, relay SY and contact *gs1* therein, relay GS in that circuit being operated over wire PO, and wire SO and wiper 55 in Fig. 4.

If an alternative route is available in case of 60 congestion of the direct route the contact in the arc of wiper DM4 appropriate to the group in question is connected to earth either directly or over a cut-off key COK which is common to all 65 the control circuits serving selectors having access to the group. When the digit switch has been set to contacts of a group for which an alternative route is available and relay PTA has been operated relay AT operates and at contact 70 75

at2 prepares a circuit for relay AN. Contact at3 directs the selector test circuit over contact an5 and contact at4 closes a point in a test circuit for high speed test relay TB for bringing about a changeover of the marking circuit from the lines of the direct route to those of the alternative route. If all the lines of the direct route are busy the selector continues in rotation until the penultimate contacts are reached. A circuit 5 is then closed from earth over contact an4, penultimate contact and wiper 6, contacts k6, gs4, (relay GS operated on receipt of the second digit "1" initiating the search), k1, wiper 7 contacts at4, gs5, relay TB to battery. Relay TB 10 operates stops the switch at contact tb1 and closes a circuit over contacts ta1, at2, an2 for the left hand winding of relay AN. Relay AN operates and locks up over its right hand winding, releases relay TB at contact an4, prepares 15 a circuit for relay OF at contact an2, closes a holding circuit for relay AT over contacts an3, at1, of2, and b1, connects wiper DM6 in place of wiper DM5 at contact an5 and at contact an6 connects relay TB to wiper DM1 to test for 20 a free storage device in case all the alternative routes are busy.

The circuit for magnet LM is closed on the release of relay TB and the switch again advances and searches for a free line in an alternative 30 route marked over wiper DM6. When such a line is found relay TA operates over contacts in6, at3, an5, wiper DM6 arc and wiper 7 thence to the battery connection on wire PO over the same route as previously traced for the testing of a direct line. The switch is stopped and relays HC, 35 H and HA operate as before.

If the selector is for any reason unable to find a free line it continues in rotation until an outlet connected to a call storage equipment appropriate to the trunk group is reached whereupon 40 it is stopped by the operation of relay TB in a circuit over contacts gs5, an6 or at4 depending on whether an alternative route was provided for the trunk group in question or not, wiper DM1 contact and wiper 7, thence over wiper 6 to earth 45 over contact rr2. Contact tb1 closes a circuit for the left hand winding of relay OF which operates and locks up over its right hand winding and contacts rr1, of1 and b1. Contact of2 releases 50 relay AT if it has been operated, contact of3 operates relay HA and contact of4 connects battery potential over contacts ha5 and h4, wiper 4 to operate the storage device. This device may follow the general lines of that described and illustrated in Specification No. 401,394. The group 55 control arrangements shown therein involving the relay GP are exemplified in the present case by a similar relay shown in Fig. 1, earth being connected over a contact of this relay to wire SO outgoing from the contacts associated with storage circuits in the arc of wiper 5 if there is a free trunk in the group.

The positive and negative wires and wire NN are switched through to the storage circuit and a 60 source of interrupted tone is applied to the positive wire to signal the operator that the call has been stored.

When a line in the required trunk group becomes free the aforesaid earth connection to wire SO is made but relay RR in Fig. 4 does not operate due to the high resistance included in the connection for this relay in the connecting circuit. The supervisory relay operates and the operator wishing to engage the trunk throws her 65 speaking key thereby reducing the resistance of

the circuit and permitting relay RR to operate. Contact rr1 opening releases relay OF and contact rr2 releases relay TB. Relay HA releases and releases relay RR. The switch is now driven in search of the free trunk and when this is found 5 relay TA operates to stop the switch and bring about the switching through of the connection by the operation of relays HC, H and HA.

If a code appropriate to a spare number is received the switch, being unable to find any 10 marked group rotates to a last contact position whereupon relay TA operates over contact gs6 or over wiper DM5 and the relevant contact which will be connected to the last contact in the arc of wiper 7, thence over wipers 7 and 6 to battery 15 connected to the last contact in the arc of wiper 6 or over wiper 7, contacts gs4 and ca6 to battery: N. U. tone is transmitted back from a tone circuit connected to the last contacts in the arcs of wipers 1 and 2.

Relay RA operates in series with magnet LM and lights lamp RAL at contact ra2 and at contact ra1 closes a circuit for delayed alarm relay.

Reference will now be had to Fig. 5 which shows a reverting first trunk selector, which is 25 provided to enable an operator to set up a connection to a trunk line over the answering side of a connecting circuit. A connection of this nature is required to re-call a subscriber whose call has been subject to delay. When the desired 30 connection is available the wanted line that is, the line which was originally asked for, is connected to the calling side of the connecting circuit and the reverting trunk selector is caused to associate itself with the answering side of the connecting circuit and is then set to select a junction line or a second trunk selector having access to a trunk line in the group over which the demand originated.

The selector comprises a motor driven 100 outlet switch MS having access to second trunk selectors and a 100 outlet motor driven finder switch FS having access to the answering side of connecting circuits. The selector is controlled by a common control circuit shown in the lower part of the drawings and which becomes connected to the selector by means of a motor driven coupling switch CS. A common control circuit serves two groups of revertive selectors and a plurality of control circuits is available to each group of selectors. The switch MS is set by a marking applied in response to a coded digit received on code relays AW—AZ in the control circuit and means is provided for transmitting forward a signal for discriminating between 55 digits of a pair as described in connection with Fig. 3.

Test relays T, TB and TD are high speed relays.

For the taking of a control circuit into use 60 two starting relays are provided one GT, associated with one group of selectors and the other ST associated with the other group of selectors. If the circuit is required in connection with a connection to be set up over a selector in one 65 group termed for convenience A and assuming a control circuit to be free relay ST is operated. This is brought about as follows: The operator, having thrown her speaking key and operated relay SK, operates key SA thereby operating relay RS in the connecting circuit and connecting earth over wire "in" A, contacts co5, gt2, a2, ta2, tc2 relay ST to battery. If the control circuit is in use relay CO or GT will be operated and the earth potential referred to will be applied over 70 75

contact co_5 or contacts co_5 and gt_2 to wire "out" A and thence to the "in" wire of another control circuit. Similarly if the connection is required to be set up over a selector in group B the earth potential will be applied to wire "in" B thence over contacts co_6 , gt_3 , st_2 to relay GT or over the wire "out" B to another control circuit.

It will be assumed for the moment that the control circuit shown is free and that the connection required is over a selector in group A. Relay ST accordingly operates and locks up over contact st_1 and the "in" wire. Contact st_2 opens the circuit for relay GT to prevent interference from an operator using another connecting circuit to set up a connection in group B, and to steer the starting signal to another connecting circuit. Contact st_5 closes a circuit for relay A which operates and locks up over contact a_1 , and contact st_7 prepares a circuit for the high speed test relay T. Contact a_2 opens in the operating circuit for relay ST and contact a_5 closes a circuit from earth over contacts t_1 , ta_1 , a_5 latch magnet CSL of the coupling switch motor, relay RA to battery. The coupling switch starts in search of a free selector in group A which is marked by battery potential on the contact in the arc of wiper CS7. When a free selector is found relay T operates in a circuit from earth over the rectifier, both windings of relay T, contacts st_1 , gt_4 , contact and wiper CS6, contact tc_4 , wiper CS7, contact k_5 of relay K in the selector, off normal contacts fon_2 and mon_2 of the finder and selecting switches respectively to battery. Contact t_1 disconnects direct earth from magnet CSL and allows relay TA to operate in series with the magnet, the magnet however releasing due to the resistance of relay TA and bringing the coupling switch to rest.

Relay TA operating opens a further point in the direct earth circuit for magnet CSL at contact ta_1 and closes a holding circuit for relay ST over contacts ta_2 and tc_2 . Contact ta_3 connects earth over contacts st_3 and co_2 , wiper CS2 and contact k_2 for relay L in the selector circuit, contact ta_4 prepares a testing circuit for the finder switch FS, contact ta_5 prepares a circuit for the latch magnet FSL of the finder switch, contact ta_6 releases relay A and contact ta_7 closes a circuit for holding relay TA by means of its winding (II) after relay A has released. Relay L operates and performs the functions of a starting relay for the finder switch, contact l_1 connecting relay K to the contact in the arc of wiper CS1, contact l_3 completing the testing circuit for relay TB, contact l_5 completing the latch magnet circuit and contact l_6 operating a traffic recorder. The magnet FSL operates in a circuit from earth over contacts tb_1 , tc_1 , st_4 , ta_5 , a_4 wiper CS5 contacts k_3 , l_5 , magnet winding, relay RB to battery. Contact fon_2 opening releases relay T. The finder switch rotates in search of the connecting circuit which started it, relay TB operating over contacts ta_4 , co_3 , wiper CS3 contact l_3 , wiper FS6, wire P, contacts rs_2 (Fig. 2), rs_3 , sk_1 , key RA, contact sk_6 , key RL, shunted relay B, to battery. Contact tb_1 brings about the stopping of the switch, and holds relay TB by its upper winding and allows relay TC to operate. Relay TC opens a further point in the circuit for magnet FSL at contact tc_1 , operates relay K over its lower winding, wiper CS1 and contact tc_3 , prepares a circuit for relay C at contact tc_4 , prepares the testing circuit of the selecting switch MS by connecting relay TD to wiper CS8 at contact tc_5 , and prepares a locking circuit for itself

over its second winding at contact tc_6 . Contact tc_2 opens in the holding circuit of relay ST. Relay ST releases now if it has not already been released consequent on the operation of relay B in the connecting circuit and at contact st_5 releases relay TA. Consequent on the operation of relay K this relay locks up over its upper winding, contact k_1 to battery over relay B (Fig. 2) wire P and wiper FS6 and at contact k_2 disconnects relay L. Contact k_3 connects latch magnet MSL of the selecting switch in place of magnet FSL, contact k_4 prepares a locking circuit for relay H, contact k_5 closes the circuit for winding (I) of relay C, contact k_6 substantiates contact k_7 and contact k_7 opens the homing circuit for the selecting switch. Relay L releases and relay C operates over wiper CS7 in series with relay H, but relay H is not operated owing to the resistance in the circuit. Contact c_1 closes the locking circuit for relay TC and operates relay CO. The code relays are now connected to the incoming positive and negative wires and wires NP and NN over make contacts of relay CO and break contacts of relays L and H. Contacts co_5 and co_6 connect the start wires "in" of each group to the corresponding "out" wires. The circuit is now ready to receive the coded digits for setting the selecting switch.

Before continuing with the setting of the selecting switch it may be convenient to refer to the operation of relay GT. If the connection is to be completed over a selector in group B relay GT is operated as previously mentioned. This relay locks up to the "in" wire independently of relay ST at contact gt_3 and at contact gt_1 brings about the operation of relay ST and at contact gt_2 connects the "in" and "out" wires of group A together to direct a start signal for group A to another control circuit. Contact gt_4 disconnects relay T from contacts in the arc of wiper CS6 associated with group A and connects it to contacts in the same arc associated with group B. The subsequent circuit operations take place as previously described, the selector being in group B.

Relay B in the connecting circuit having operated the answering supervisory lamp ASL lights and the operator may then start the transmission of the first code marking. This is received and recorded by the operation of one or a pair of the code relays which apply a marking over relay TD and one of the wipers CS9-CS15 shown for convenience as one wiper and arc of contacts to the arc of wiper MS8. Contacts 6 of the code relays operate relay CT which closes the circuit for magnet MSL over contacts td_1 , te_2 , and wiper CS5. The selecting switch rotates until a free line in the marked group is reached whereupon relay TD operates over contact tc_5 the marking contacts of the code relays, one of the wipers CS9-CS15, contact and wiper MS8, wiper MS6, wire P to battery in the second trunk selector. Contact td_1 brings about the stopping of the switch, holds relay TD by its upper winding thereby busying the outlet and allows relay TE to operate. Relay TE locks up over its winding (II) and contacts te_1 and c_1 and at contact te_2 opens a further point in the circuit for magnet MSL. Contact te_5 opens the circuit of the code relays to bring about the operation of relay DS in the register sender and contact te_3 short circuits relay C and allows relay H to operate. This relay locks up over contacts h_1 and k_4 and at contact h_3 operates relay HA. Further contacts of relay H and contact ha_1 switch the connecting

circuit through to the second trunk selector and contacts *ha2* and *ha3* open in the homing circuits for switches FS and MS. Relays TD and CT release.

- 5 If the code received was such as to necessitate the transmission forward of a discriminating signal relay PP would have been operated over its winding (I) and contacts of the code relays cross connected as required to an earthed terminal PD. Contact *pp2* would then hold relays TC, TE, and CO and contact *pp1* would connect winding (II) of relay PP over contacts *te4*, wiper CS8, and contact *ha4* and wiper MS7 firstly to battery over the back of contact *jb1* in the second trunk selector and after the operation of relay JB over a front contact of this relay and magnet DM. When the digit switch in the second trunk selector control circuit reaches its 12th contacts to which it is stepped consequent on this 10 earth connection relay PP releases. The release of relays PP and C bring about the release of relays TC, TE and CO and the control circuit assumes its normal position.

If no outlet to a free second trunk selector in 25 the marked group is found switch MS rotates to a last contact position in which relay TD operates over contacts *tc5*, *te4*, wiper CS8, contact *ha4*, last back contact and wiper MS8, wiper MS6, last contact, contact and wiper CS16, contact *ct2* to battery. Relays TE, H, and HA operate and busy 30 tone is applied to last contacts in the arcs of wipers MS1 and MS2. Battery over wipers MS4, FS4, and wire NN releases the sender in a manner which will be clear from a consideration of the 35 circuits shown in Fig. 6.

If the code received is indicative of a spare group or is not used for the group of trunks connected to the selector in question a cross connection will exist between the arcs of one of the 40 wipers CS9-CS15 and the last contact position the first half of the bank of wiper MS8, that is, the 50th contact which is reached after the first half revolution of the selecting switch wipers and the switch will be stopped in this position by 45 the operation of relay TD over the marking circuit traced and wiper MS6 to battery. N. U. tone will be applied over the corresponding contacts in the arcs of wipers MS1 and MS2 and the sender will be released as in the case of an all lines busy 50 condition.

When the connection is terminated the operator disconnects earth from wire P thereby releasing relay K. Contact *k4* releases relay H which releases relay HA and homing circuits are 55 closed; for switch FS from earth over contact *fon1*, *ha2*, *k1*, *l5*, magnet FSL relay RB to battery and for switch MS from earth over contacts *k6*, *mon1*, *ha3*, magnet MSL, relay RB to battery, contacts *fon1* and *mon1* opening and 60 contacts *fon2* and *mon2* closing when the switch reaches its normal position.

As before mentioned the coupling switch has no normal position. Whenever it passes through its first contact position contact *con* opens and 65 relay A being operated at this time relay TL operates. Contact *t11* removes the short circuit from relay TL which would otherwise be effective when the switch steps off the first contacts and contact *con* closes and completes a circuit 70 for relay TM. When the switch, after making a complete sweep of its bank and finding no free selector reaches its last contacts position it is stopped by the operation of relay T in a circuit over wiper CS6, contact *tc4*, wiper CS1, contacts *a6*, *st6*, *tm1* to battery. Relay TA will not 75

operate as with these connections its two windings oppose one another. Earth is connected periodically over a wire EP and contact *a7* for a time sufficient to release relay TM which in turn releases relay T and the switch commences another search, the interval between successive applications of earth to wire EP being sufficient to allow for the release of relay TM and the sweep of the switch over its bank and a suitable resting period. Each time magnet CSL is operated relay RA operates and at contacts *ra1* 10 closes a circuit for a delayed alarm relay and at contact *ra2* connects lamp RAL to earth over an interrupting contact. Similarly, relay RB operates whenever magnet FSL or MSL is 15 operated to close the circuit of the delayed alarm relay at contact *rb1* and light lamp RBL steadily at contact *rb2*.

The operation of the sender shown in Fig. 6 20 will now be considered.

Six sets of register relays AW-AZ, BW-BZ . . . FW-FZ are provided of which sets DW—, EW—, and FW—, are not shown but their connections are similar to those shown for set CW—, the relays of the sets being connected to the 25 4th, 5th, and 6th contacts in the arcs DD3-DD6 and their marking contacts being arranged similarly to those of set AW—, and it may be arranged to record 8 digits on these registers by using register relay sets AW —, and BW —, twice 30 over. For the setting of selector switches in the trunk exchange up to four settings may be effected by marking, these being sufficient to route the call over the trunk selectors to a trunk or junction line or to local switches, the remainder of the switches to be set from the sender 35 being set by impulses transmitted in the usual manner. The switch DD acts as a digit distributor and also serves as a controller to control the application of the markings or the transmission 40 of impulse trains in turn. It is a 7 wiper ratchet driven uniselector of the reverse drive type the magnet being designated DDM. SS is a 5 wiper ratchet driven uniselector of the reverse drive 45 type which performs the duties of a sending switch for impulse transmission; its magnet is designated SSM.

For the purpose of marking the sender bank, contacts of the register relays are provided and arranged in the commonly known tree formation. Since at least one digit must always be 50 transmitted for getting out of the trunk exchange a marking of the sender switch bank in respect of the first stored digit is not required. The contact tree of relay set AW—, shown in 55 full provides for a marking in respect of a 7th digit and contacts of relay set BW— provide for a marking in respect of a 2nd and an 8th digit depending on the condition of relay ED. The contact trees of the registers for the 3rd to the 6th digits are not shown in full but are indicated 60 by a line connection between the arc of wiper DD2 and the sender multiple, their connections being similar to those shown for the AW— relay set.

The markings of selecting switches in the trunk exchange is effected over the wires +, —, NP and NN and wipers DD3-DD6 of the digit 65 distributors and relays TT and TS.

The sender is one of a number common to the 70 trunk switchboard as a whole and is connected to an operator's position when required by a motor driven hunting switch SCS. Senders are connected to a chain start circuit the first free sender being taken into use by a start signal over 75

wire "in" and when connection with the operator's position has been made the start wire "in" is extended to the wire "out" which forms the "in" start wire of the next sender on the chain.

5. The operation of the sender circuit will now be described in detail.

An operator requiring a sender having thrown the send call key SCK, or the send answer key SAK, as the case may be, earth is applied to 10 wire "in" which, if the sender shown in the figure is free operates relay ST. Contact *st1* connects high speed relay T to the test wire P which is connected to battery over a shunted reed relay in the position circuit, contact *st2* closes a circuit 15 from earth over contact *t1* for latch magnet SCL of the sender coupling switch and contact *st3* maintains the circuit for relay ST by bridging contact *on2*. The switch is started and hunts for the marked position, and when this is 20 found relay T operates, releases the magnet SCL and removes a short circuit from relay H at contact *t1* and short circuits the right hand winding of relay T to bring wire P nearer to earth potential and to mark the position circuit 25 engaged to other senders. Relay T holds by its left hand winding and the shunted relay in the position circuits operates in series with it to disconnect the starting earth from wire "in" and light a lamp to indicate that the sender has 30 been connected up. Relay ST releases slowly and relay H operating contacts *h1-h4* connect the wires NP, NN, +, - from the key strip in the position circuit to wipers DD3-DD6 which 35 connect up the several registers in turn. Contact *h5* holds relay T after the release of relay ST, contact *h6* prepares a circuit for the cancelling relay CK, contact *h7* opens in the homing circuit for the switch, and contact *h8* operates relay HA. Relay HA operating contact *ha1* 40 prepares the locking circuit for the register relays over their right hand windings, contact *ha2* opens a point in the self drive circuit for switch DD in the 10th to 25th position of that switch, contact *ha3* prepares a circuit for cut off relay 45 CO, contact *ha5* connects relay S to wire SST to receive the "start sending" signal, contact *ha6* connects the "in" start wire to the "out" start wire, contact *ha7* lights lamp RAL over key contacts BK2 and contact *b3* and contact *ha8* holds 50 relay H. The operator seeing the "sender engaged" lamps glowing keys up the number indicative of the connection required. The keys pressed apply earth potential transitorily to one or a combination of the wires connected to 55 wipers DD3-DD6 bringing about the operation of corresponding register relays. In general the digits are received as follows. For the first digit one or more of the relays AW-AZ operate over their left hand windings, contact *t* in the arc 60 associated with wiper DD7, contact *s1*, upper winding of relay DS to battery and lock up over their right hand windings contacts *sd2*, *ck2* and *ha1*. Relay DS operates in the above traced circuit and at contact *ds1* connects earth over contact *s4* to magnet DDM and lower low resistance 65 winding of relay BP, contact *ds2* opens in the circuit for relays TT and TS, contacts *ds3* and *ds4* will be referred to later. When the digit key is released relay DS releases and the switch DD 70 is stepped to its second contacts on the release of its magnet DDM by the opening of contact *ds1*. The second digit is received in a similar manner on the relays BW-BZ, the operating circuit including contact *2* in the arc of wiper DD7, the locking circuit including contact *ed4* but not 75

contact *sd2* and the distributor is stepped to its third contact. In the 3rd to the 6th positions the 3rd to 6th digits are received on combinations of relays similar to those shown and which lock up directly over contacts *ck2* and *ha1*. If a 5 7th digit is to be recorded relay SD will have been operated to release the relays AW-AZ at contact *sd2* and to re-connect them in a circuit over contact *7* in the arc of wiper DD7. A locking circuit is provided by closed contacts of relays FW-FZ. Similarly if an eighth digit is to 10 be recorded relay ED will have been operated to release relays BW-BZ and to reconnect them in a circuit over contact *8* of the arc of wiper DD7. After all the digits have been recorded the operator 15 presses her start key in the key strip thereby earthing wire SST and operating relay S.

Contact *s1* disconnects the upper winding of relay DS, contact *s5* prepares a circuit for the lower winding of the same relay by which the 20 relay controls the switch DD in its function of controller, contact *s2* connects earth over wiper DD1 and contact *ddm* of magnet DDM to this magnet which by self interruption drives the switch to its 10th position. Contact *s3* opens the 25 circuit of the cancelling relay CK and contact *s4* prepares the stepping circuit for magnet DDM to step the switch as a controller. Contact *s6* includes contact *ds4* in the circuit over wiper DD4.

Consequent on the pressing of the start key in the position circuit the sender is disconnected from the key strip and connected over one side or other of the connecting circuit to the first 30 trunk selector or reverting trunk selector as the case may be and the wires +, -, NP, and NN are extended to the circuit of this selector where they are connected to earth over a code relay in each wire. A circuit is now completed as follows, earth over the code relays in the selector 35 circuit, the said wires, wipers DD3-DD6 in their 40 10th position contacts *2* of the code relays operated by the first digit, contacts *cc2*, *ds2*, relays TT, TS contact *tt2* to battery. Relays TS and TT are operated in this circuit, contact *tt2* 45 opening after contact *ts1* has closed since relay TT is a slower relay than TS which is of the high speed type, thereby leaving this circuit dependent on relay TS. Contact *tt1* prepares a 50 circuit for relay DS and contact *tt3* for magnet DDM. The code relays in the first trunk selector are operated in the above traced circuit the 55 relays operated depending on the register relays for the 1st digit operated in the sender, and as soon as a free outlet has been found by the selector, which is a high speed motor driven switch the circuit over the code transmitting wires is opened and release of relay TS takes place. This relay on releasing its only contact 60 opens the code signalling circuit and brings about release of relay TT. Before relay TT releases relay DS operates over its lower winding, contacts *s5*, *tt1* and *ts1* closing a circuit over contacts *tt3*, *s4* and *ds1* for magnet DDM which 65 operates and on the subsequent release of relay TT releases and steps the switch one contact. Contact *ds4* connects winding (I) of relay XY to wire NN to test for a busy signal. In its second position the distributor connects the code 70 signalling wires to contacts of the second set of register relays and a marking of the second trunk selector is effected in a manner similar to that just described. Each digit for the operation of selectors in the trunk exchange is transmitted in a similar manner, a maximum of 4 75

such digits being catered for. When the last selecting switch in the trunk exchange has been set an outgoing relay set is encountered which applies battery over one or more of the signalling wires —, +, NP which, on the operation of relay DS to bring about the stepping of the distributor and to connect winding (I) of relay CC to the code signalling wires operates relay CC which thereupon locks up over its winding (II), contacts *c1* and *h1*.

Before continuing with the operations following on the operation of relay CC reference will be made to certain special cases. The above described operations are those which take place if only 6 digits are to be transmitted or if the first digit is not a particular digit dialled to cause the first trunk or reverting selector to select an outlet to a local exchange or if the first and second digits are not a particular combination such as may be employed for gaining access to special trunk offering lines. If the first digit is the particular digit referred to relays AX and AY are operated and contact *ds3* opening due to the operation of relay DS on receipt of this digit opens a circuit over contact *ay3* and *ax3*. On the subsequent release of relay DS relay SD is operated over its winding (I) contacts *aw3*, *ax3*, *ay3* and *ds3*. The relay locks up over its winding (II) contacts *sd1*, *ck2* and *h1* and at contact *sd2* opens the locking circuit for the register relays for the first digit. Contacts *sd4* and *sd5* substantiate contacts *ax2* and *ay2* to provide the required marking circuit, contact *sd3* connects contact *1* to contact *1* in the arc of wiper DD7 to enable a seventh digit to be registered on the relay set AW—if necessary and contact *sd6* prepares a circuit for marking the sender for the seventh digit. If the particular combination of first and second digits is received relays AW, AY, BX, and BY will be operated and on release of relay DS after the receipt of the second digits relays SD and ED will operate in a circuit over windings (I) of both relays, contacts *by3*, *bx3*, *aw4*, *bw3*, *ax3*, *ay3*, and *ds3* and the relays will lock up in parallel over their second windings. Contacts of relay SD perform the functions already referred to, contact *ed2* makes connections over wiper DD7 for receiving an eighth digit on the relay set BW—, contacts *ed3*, *ed5* and *ed6* substantiate contacts *aw2*, *bx2* and *by2* to provide the marking circuits for the transmission of the two digits to the selectors concerned, contact *ed4* releases the register relays for the second digits and contact *ed7* provides for a marking of the sender by an eighth digit.

The first two digits in the latter case are transmitted by markings over relays TS and TT, contacts *ed3* and *ed5* and wires NP, +, for the first digit, and over the same relay and contacts *ed5* and *ed6* and wires NN and + for the second digit. The circuits for the transmission of the particular first digit will be seen to be over contacts *ed3*, *sd4* and *sd5* and wires NN and +.

When a line leading out of the trunk exchange has been selected relay CC is operated and locked up as above mentioned. Contact *cc2* opens its operating circuit and the circuit for the code marking of the selectors, contact *cc3* opens to prevent the sender self driving in a circuit to earth over wiper SS1, contact *cc4* prepares a circuit for relay IG and for homing the sender, contact *cc5* prepares a stepping circuit for the distributor dependent on the sender reaching its 21st position since relay DS is now disabled, contacts *cc6* and *cc7* disconnect wires + and —

from the distributor wipers DD5 and DD6 and connect them to interrupter springs 12 for the purpose of transmitting impulses over a loop circuit formed over these two wires, the loop being at the moment closed over wiper SS5. Contacts I1 and I2 are operated at a predetermined speed, for example 10 times a second, one contact opening at the time the other closes. When contact I1 opens for the first time after relay CC operates, relay IG operates in a circuit from earth over contacts *co4*, *cc4*, wiper SS3 in position 1, contacts *ss2*, *ss3*, relay IG to battery. Contact *ig1* changing over prevents the relay being short circuited when contact I1 again closes and extends earth over wiper SS3 to magnet SSM which operates in series with relay BP when contact I1 is closed and the sender is stepped to its second contacts on the subsequent opening of contact I1. Here a stepping circuit for magnet SSM is prepared over contact *ss3* and is closed each time contact I1 closes to step the sender in search of the contact marked over wiper DD2 and the relevant contact in the arc and the tree of contacts of the register relays corresponding to the first digit to be transmitted by impulses. When the sending switch is stepped to its third contacts the short circuit across the impulse springs 12 imposed by the wiper SS5 is removed and the loop is then opened each time springs I2 open and an impulse is transmitted. When the marked contact is reached relay SZ operates in a circuit from earth over wiper DD2, contact tree, wiper SS2, winding of the relay to battery and locks up over contact *ss1* and wiper SS1. Contact *ss5* short circuits the impulsing springs I2, contact *ss3* opens the stepping circuit for switch SS and closes a self driving circuit over which the switch drives to its 21 position and contact *ss4* closes a circuit for relays IG and a stepping circuit for switch SS. The sender is stepped to its 25th position in a circuit over contact I1 where a circuit is closed over contacts *ss3* and *ssm* to step the switch to its 1st position. Here the switch is brought to rest, contact *ss2* being open, and relay SZ releases re-closing the circuit over contacts *ss2* and *ss3* to start the sending switch searching for the next marked position. When the sending switch reached its 21st position the earth over wiper SS3 was extended over wiper SS4 and contact *cc5* to magnet DDM and the distributor was advanced one step to connect up the next marking. Stepping of the distributor in this manner continues until all the digits to be sent have been sent. If these are 8 in number, 2 at least of them will have been sent by the marking method and when wiper DD2 reaches its 16th position, corresponding to the 7th digit position, the sender is marked over this contact, contact *sd6* and the contact tree of relay set AW—. Similarly the 8th digit is marked over position 17 of wiper DD2, contact *ed1* and contacts of relay set BW—. If less than 8 digits are to be transmitted then, after the stepping of the digit distributor after the last digit has been transmitted earth over wiper DD2 will be extended over unoperated contacts of the register relays, contact *ddm* to magnet DDM and the distributor will be stepped to its 18th position. In this position relay CO operates over its winding (I) and wiper DD2 and locks up over contact *co2*. Contact *co1* prepares a holding circuit for the relay over its winding (II), contact *co3* closes a circuit for winding (III) of the relay to ensure its holding until the sender has reached its normal position, contact *co4* opens the homing cir-

cuit of the sender which, for homing is then dependent on wiper SSI after relay CC has released, contact co_5 releases relay H, contact co_6 maintains the through starting circuit after release of relay HA and contact co_7 operates and holds relay BP. Winding (II) of relay CO takes care of the case in which the operator releases the sender by releasing the send call key after one digit has been set up by means of the key strip but before the start sending key has been pressed. In these circumstances relay S will not have been operated and relay T is released. Contact t_1 short circuits relay H which at contact h_8 opens the circuit of relay HA and operates relay CO by means of its winding (II). After the release of relay HA relay CO holds over its winding (II), contacts co_1 , s_2 and wiper DD1 to earth until the distributor reaches normal, the distributor being homed in a circuit from earth over wiper DD1, in positions 1 to 9 and contacts s_2 and h_8 in positions 10 to 25 directly over contacts h_8 and ddn . Reverting to the normal operation when relay H releases relay HA is released at contact h_8 . Contact ha_1 falling back closes a self drive circuit over wiper DD1 for magnet DDM and the distributor is driven rapidly to normal. Opening of contact ha_1 releases relay CO, the locked register relays and relays SD and ED if they have been operated and contact ha_3 opens the holding circuit for relay H. Contact cc_3 closing the sender is homed in a circuit extending from earth over wiper SSI, contacts cc_3 , ssm to the sender magnet. When both switches are again at normal the circuits for relay CO are all open and that relay releases and restores the starting circuit for switch SCS. The release of relay H closes the homing circuit for the sender coupling switch from earth over contacts h_1 , on_1 , of the switch SCS, st_2 magnet SCL to battery and the switch is rapidly driven to normal where its motor circuit is opened at contact on_1 . Contact on_2 , closing in the normal position of the switch reconnects relay ST to the "in" wire after the release of relay CO. Opening of contact h_5 releases relay T and extinguishes the "sender engaged" lamp at the operator's position, and the opening of contact ha_5 releases relay S and effects the opening of the circuit over wires P and "in" at the position circuit to prevent a re-engagement of the sender.

If a first trunk or reverting selector encounters a busy condition and is arrested in a "last contact" position the transient signal transmitted as a result of the change over of the contacts of the switching relay in the wires over which the code marking is applied effects operation of relay TS as for switching through to a subsequent selector. Relay DS operates during the release period of relay TT and during this period battery connected over a wiper of the selector and wire NN brings about operation of relay XY over contacts h_2 , s_6 , ds_4 and winding (I) of the relay. Relay XY locks up over its winding (II), contacts xy_1 and co_5 . Contact xy_1 changing over release relay H which operates relay CO by means of its second winding at contact h_8 and at contact h_5 releases relay T and extinguishes the "sender engaged" lamp in the position circuit. Contact co_5 opening prevents re-operation of relay H and releases relay XY, and contact co_1 in conjunction with contact ha_2 of relay HA which was released by the change over of contact h_8 closes the homing circuit for the switch DD. This switch and the sending switch are homed

and the circuit restored to normal in the manner above described.

If, before the start sending key is pressed by the operator the cancel key is pressed earth is applied to wire CL and relay CK operates. Contact ck_2 releases the register relays already operated and contact ck_1 provides a holding circuit for relay CK over its winding (II) and contact s_2 to earth over wiper DD1. This second winding is a low resistance one and besides its connection over contact s_2 to contacts 1 to 9 in the arc of wiper DD1, it is connected directly to contacts 10 to 25 of the same arc and provides a circuit over which magnet DDM operates and homes the distributor. Relay CO operates in position 18 of wiper DD2 and brings about the disconnection of the sender and the extinguishing of the lamp at the operator's position. If the send call (or send answer) key is still thrown then another sender is taken into use by the extension of the start circuit over contact co_6 .

Whenever magnet DDM or SSM is operated relay BP operates. The relay is also held operated by contact co_7 during the releasing operations. Relay BP operating the left-hand winding of relay A is connected over contact bp_2 to wire SA which is earthed periodically. On operation relay A connects its right hand winding in series with the left hand winding of relay B over contacts a_1 and bp_1 and at contact a_2 connects the right hand winding of relay B to wire ZA which is earthed periodically after the elapse of a predetermined interval after wire SA is earthed. Relay B will not operate by means of its left hand winding in series with relay A. When earth is connected to wire ZA relay B operates, short circuits the right hand winding of relay A over contact b_2 to delay its release and opens the circuit of the left hand winding of relay A. Contact b_3 connects lamp RAL to an interrupted earth to flash the lamp, contact b_4 closes the circuit for an alarm device and contact b_5 lights an alarm lamp.

The sender may be artificially busied at any time by throwing the key BK. Contacts BK_1 connect the "in" and "out" start wires together and cut out relay ST, contacts BK_2 connect steady earth to lamp RAL and contact BK_3 prevents operation of the alarm device.

I claim:

1. In a telephone system, selecting switches, a marking device for each switch register senders, means for transmitting digits to a plurality of registers in turn, means for subsequently connecting the selector switches for use and for connecting the registers to the marking devices of the selectors, each register having means for transferring its setting in code to a marking device, each device effecting marking connections for setting its selector switch in accordance with the received code.

2. A telephone system as claimed in claim 1 in which each selector switch has common apparatus including a single motion switch and a set of code relays said code relays marking the bank of the single motion switch, and said switch operating to find said marking to thereby mark the bank of the selector switch.

3. In a telephone system, a selector switch, lines accessible thereto, common control equipment for said switch, said equipment including a single motion switch and a set of code relays, means for transmitting coded digits to the switch, said code relays operating in response to the first digit to mark the single motion switch and to cause said switch to operate to assume said marked position

and release the relays, said relays operating in response to the second digit to apply a marking to the bank of the selector switch through a wiper of the single motion switch in the position to which it was operated.

4. In a telephone system, a first selector switch, a plurality of second selector switches accessible to said first switch, a marking device for each switch, register senders, means for transmitting digits to a plurality of registers in turn, means controlled by one register for controlling the marking device of the first selector and to cause said selector to operate in response to such marking to seize one of said second selectors, and means in the first selector operated when a second selector is seized for transmitting a signal to the register sender, said sender responsive to said signal to transmit a code for marking the seized second selector switch.

5. In a telephone system, a register sender, switches controlled thereby, means for setting the sender in accordance with a digit, means in the sender controlled by said setting for transmitting digits either in code form or by series of impulses, means responsive to the transmission of a coded signal by the sender for setting a switch, and means responsive to the seizure of an outlet by the switch for transmitting a signal to the sender to cause the sender to transmit the next digit either by means of a series of impulses or by another coded signal.

6. In a telephone system a register sender, switches controlled in turn by said sender, means for setting the sender in accordance with a digit, means in the sender for transmitting a first digit to a switch in code form, and means in the sender for transmitting the next digit to a subsequent switch in the form of a series of impulses.

7. In a telephone system, an operator's circuit, automatic switches accessible to said circuit, a group of code relays for each selector, registers, means controlled by the operator for transmitting digits to the registers, means controlled by the registers for successively controlling the code relays of the automatic switches in accordance with the setting of the registers, said code relays marking each selector when set and causing its selector to find the marking.

8. In a telephone system, selector switches, marking devices common to said selector switches, a register sender comprising a plurality of registers, means including a single motion stepping switch for successively setting said registers in response to the receipt of successive coded signals, means for subsequently connecting the selector switches for use and said single motion switch thereafter successively connecting the registers to the marking devices associated with the selectors taken into use, each register having means for transferring its setting in code to a marking device, each marking device effecting marking connections for setting the associated selector switch in use in accordance with the received code.

9. In a telephone system, a register sender comprising a plurality of registers, means including a single motion stepping switch for successively setting said registers in response to the receipt of successive coded signals, selectors controlled by said sender, means in said sender including said single motion switch for successively transmitting digits in code form or by series of impulses in accordance with the successive

registrations, means responsive to the sender transmitting a digit in code form for setting a selector switch, means responsive to the seizure of an outlet by the selector switch for transmitting a signal to said sender, and means in said sender responsive to said signal for causing said sender to transmit the next digit by means of a series of impulses.

10. In a telephone system, a register sender comprising a plurality of registers, means for successively setting said registers in response to the receipt of successive coded signals corresponding to the digits in a telephone number, selector switches controlled by said sender, means in said sender for successively transmitting the digits of said telephone number in code form or by series of impulses in accordance with the successive registrations to successively control the operation of said selector switches, and means whereby one of said registers is used for two digits of the same telephone number, the first digit setting of said register being transmitted to a selector switch in code form and the second digit setting of said register being transmitted to a selector switch by means of a series of impulses.

11. In a telephone system, a selector switch, a sending device, means for operating said sender to transmit a code, a group of code marking relays, certain of said relays in said group operate in accordance with said code, a plurality of marking circuits for controlling the operation of said switch, one of said marking circuits completed in response to the operation of said certain relays, and means for operating said switch in accordance with said completed marking circuit.

12. In a telephone system, registers, operator controlled means for transmitting digits in code form to set said registers, trunk selecting switches, code relays associated with said switches, means for transferring the setting of said registers to said code relays, means for setting said selector switches in turn in accordance with the settings of said code relays, a trunk line engaged by the last set selector switch, a connecting circuit associated with said trunk line by way of said set selector switches, a repeater associated with said connecting circuit, provided with a plurality of fixed values of gain, and means for inserting said repeater in circuit with said connecting circuit with one of said fixed values of gain dependent upon the trunk line associated with said connecting circuit.

13. In a telephone system, selecting switches, code responsive devices associated with said switches, a register sender, means in said sender for transmitting digits comprising signals in code form to said code responsive devices in turn, means for marking said selector switches in response to the operation of said code responsive devices by said transmitted signals, means for operating a selector switch to find said marking, means responsive to said selector finding a marked line or a free line in a marked group for disconnecting the associated code responsive device and for transmitting a signal to the register sender, and means in said sender responsive to said signals for transmitting the next digit to the next code responsive device to control the operation of the next selector switch.

14. In a telephone system, selector switches, marking devices common to said selector switches, a register sender comprising a plu-

rality of registers, means for successively setting said registers in response to the receipt of successive coded signals, means for subsequently connecting the selector switches for use and rendering said first means operative for successively connecting the registers to the marking devices associated with selectors taken into use,

each register having means for transferring its setting in code to a marking device, each marking device effecting marking connections for setting the associated selector switch in use in accordance with the received code.

BERNARD ANTHONY HENSLER.
